SUSPENDED FURNACE ARCH

Robert A. Banck, Detroit, Mich., assignor to
Bigelow-Liptak Corporation, Detroit, Mich., a
corporation of Michigan

Application August 12, 1950, Serial No. 179,047

2 Claims. (Cl. 110—99)

1

This invention relates to soaking pits, heavy duty furnaces, and heating or combustion chambers in general, and in particular refers to their covers, roofs, or arches.

In installations of the type indicated, the covers or roofs are constructed of individual refractory bricks or tiles that are suspended by suitable means in such relationship to each other as to form a ceiling for the combustion chamber. The present invention provides a construction of tile and suspending means that has several desirable features and advantages from the standpoint of function and performance as well as erection and repair costs.

One of the desirable features of the construction described herein is that localized areas of tiles may be readily removed and replaced without disturbing adjacent tiles or their suspending means. This greatly facilitates repairs since in many cases only isolated areas become damaged while the remainder of the roof is in good condition.

Another feature of the invention resides in construction of the tiles and suspending means which is such that special contours may be obtained and yet cracks and crevices through which air could readily pass are eliminated and the tiles remain in close contact throughout the range of temperatures to which they are subjected in service. This improves combustion efficiency in the furnace and also tends to protect the supporting structure from heat escaping by convection.

Another feature of the invention enables a reduction in heat loss by radiation without inviting failure of the metallic arch or roof support. This results from the use of novel hangers as the suspending means for the tiles which are of a shape that can be readily and economically made from alloy steels capable of withstanding the high temperatures over the furnace roof. Insulation to reduce heat losses can then be laid over the roof without danger of weakening the hangers. In some cases, the insulation also permits smaller tile to be used thus obtaining the advantages of lower material and erection costs as well as greater resistance to spalling.

A feature of practical importance is that certain of the metallic tile suspending elements are exposed to cooling air which by reducing operating temperatures increases the effective strength of the elements and, in some cases, make it possible to eliminate much of the steel structure conventionally used.

A further feature of the invention consists in the support of more than one tile on each hanger. This reduces materially the number of hangers which, in turn, reduces cost and the weight suspended on the supporting structure and also facilitates installation and repair.

Also an important feature is the simplicity of the design of the suspending means and the tile which enables them to be manufactured at lower

2

cost, it being possible to manufacture certain elements of the suspending means from standard structural materials.

Other features of the invention will appear upon consideration of the accompanying drawings, in which:

10 Fig. 1 is an isometric view with parts removed and broken away of a roof embodying the invention;

Fig. 2 is a section through a set of tiles supported on one form of suspending means of this invention;

Fig. 3 is an enlarged view of the hanger bar construction within the circle 3 on Fig. 1;

15 Fig. 4 is an enlarged cross section taken on line 4—4 of Fig. 2;

Fig. 5 is an isometric view of a modified form of the invention;

Fig. 6 is a side elevation, broken away, of another modification of the invention; and

20 Fig. 7 is an elevation taken from the left of Fig. 6.

The roof fragmentarily shown in Fig. 1 is intended to typify the various installations which 25 may benefit by the present invention. The roof truss or supporting structure comprised of beams 1 may obviously be of various constructions and be supported itself in any suitable manner, for example, the beams may rest on the side walls of the furnace or other structure.

In accordance with the invention, the ceiling surface for the chamber covered by the roof is provided by the bottoms of two different types of blocks of suitable refractory material, identified by the reference numerals 3 and 5. These blocks, referred to herein as tiles or bricks, are carried by lower ends of hangers 7 which, in turn, are supported on hanger bars 9. The hanger bars 9 extend transversely to the beams 1 and are shiftably suspended on them, this being accomplished by U shaped anchor bolts 11 on the beams 1 that extend through slots 13 in vertical flanges 15 formed integrally on the bars 9. Layers of insulation 17 may be placed over the top ends of the tiles or bricks 3 and 5 and around the hangers 7 and below bars 9.

Each hanger 7 carries the weight of two tiles 3 and one tile 5. The tiles 3 are directly supported on the bottom of the hanger while the tiles 5 are directly supported on the two adjacent tiles 3 as readily observed in Fig. 1. The tiles 3 are basically similar in shape to a rectangular parallelopiped and their sides which are parallel to the direction of the bars 9 will be referred to by reference numerals 19 and 21, and their sides which are transverse to the bars 9 will be referred to by numerals 23 and 25. The sides 21 are offset inwardly adjacent the tops of the tiles 3 as shown at 27 and the bottoms of the offset portions 27 are undercut as shown at 29, it being observed that the top surface 31 of the undercut 29 is inclined downwardly in the direction of the side 21. The tops of sides 19 of the tiles 3 are offset inwardly as

shown at 33 to provide upwardly presenting shoulders 35 for supporting the tiles 5. The sides 23 and 25 are provided, respectively, with complementary, transverse, integral tongues and grooves or keys 35 and keyways 37 that are offset with respect to the general planes of these sides. The tongues or keys 33 fit in the grooves or keyways 37 of the adjacent tiles 3 and serve to interlock the tiles as well as to substantially interfere with air or gas flow through the assembled roof. It will be observed in Fig. 1 that in the adjacent rows of tiles 3 that are suspended from the same hanger bar 9, the tiles are preferably facing in opposite directions, thus serving to improve the structural integrity of the roof and also eliminating the necessity for making left hand and right hand tiles.

In order to support the pairs of tiles 3, each hanger 7 has feet or flanges 39 extending upwardly and outwardly from the bottom thereof on an angle that is preferably the same as that of the tile surfaces 31 which rest on them. It will be seen that the reaction forces of each flange 39 to the gravity load imposed on a hanger 7 by a pair of tiles 3 have horizontal components, due to the inclination of surface 31 and flange 39, which force the tiles 3 together and hold them in intimate contact regardless of expansion and contraction during operation of the furnace. While this tends to prevent leakage of air along the juxtaposed sides 21, these sides are preferably also complementarily recessed to provide grooves 41 for mortar 43. The mortar bodies 43 in the grooves 41 provide offsets to air or gas flow between the tiles 3 of a pair and thereby render it unnecessary to make left and right hand tiles in a pair.

The shanks or hangers 7 extend upwardly from the flanges 39 to terminate in heads 45 that are mounted inside of the hanger bars 9. The heads 45 have downwardly presenting shoulders 47 that are wider than the width of the lengthwise slot 49 in the bar 9 through which the shanks of the hangers 7 extend and which rest on the surfaces 51 of the bar walls adjacent the slot whereby the bars support the hangers 7 and the tiles. The shoulders 47 are rounded and preferably cylindrical as are the wall surfaces 51 on which they rest. As evident from Figs. 2 and 4, by rounding the shoulders 47, the hangers 7 can rock somewhat on the bar 9 to permit adjustment of the tiles such as may result from the influence of the reaction forces of feet 39 or thermal forces. If the shoulders 47 and surfaces 51 are cylindrical, as illustrated, this rocking is permitted only in the plane of the drawing but not in the plane of the bar inasmuch as the engaging surfaces are flat with respect to pivotal movement about an axis transverse to the bar 9 (Fig. 4). This feature prevents accidental twisting of the hangers 7 in the bars and this is important because the heads 45 are of less thickness than the width of the slot 49. However, due to the fact that the heads 45 may be removed through the slot 49, each hanger 7 may be dropped from the bar 9 by angularly turning it 90 degrees about the axis of its shank and then axially translating it downwardly. This angular movement of the hanger 7 takes place, ordinarily, relative to the tiles 3 and is accomplished by lifting the tiles from underneath so that the flanges 39 contact the bottom surfaces of undercuts 29 and are thus free to rotate relative to inclined surfaces 31. This contact and lifting also forces the head shoulders 47 off their seats 51.

It will be recognized that this simple mode of connection and disconnection makes it possible for but one hanger 7 at a time to be removed from the bar 9 without disturbing adjacent hangers. Thus, localized repair of tiles and hangers 7 is possible without interference with adjacent tiles or hangers. Stop surfaces 53 (Fig. 3) may be formed at the ends of the bar surfaces 51 to prevent the hangers 7 from sliding out of the bars 9.

It will also be recognized that the hangers 7 are of a shape that may be readily cast or fabricated from alloy steel or from cast iron which maintains its strength at elevated temperatures. This shape is also such that there are no areas of excessive stress concentration so that the hangers 7 are very efficient and thus of a minimum weight. These factors make it a practical possibility to also add the weight of the insulating layers 17 to the hangers 7, for the purpose of reducing radiation losses, without inviting failures of the hangers due to overheating and without unduly increasing the size and cost of the suspending means. The use of insulation 17 may also make it possible to use smaller tiles 3 and 5 than in the conventional suspended wall. The smaller tiles are desirable because of greater resistance to spalling, lower material costs, and lower erection costs.

The foregoing description has shown how the tiles 3 are supported by hangers 7 on the bars 9. If desired, these tiles may be used exclusively or with intermediate rows of standard bricks which rest on shoulders 35. However, it is preferred to use tiles 5 which, as evident from Fig. 1, are directly supported on the tiles 3 and thus carried by hangers 7 and bars 9. A row of tiles 5 is supported between each pair of hanger bars 9 on the tiles 3. The tiles 5 are basically rectangular parallelopipeds but have flanges 55 at the top thereof which extend transversely to the bars to fit in offsets 33 in the tiles 3 and to provide downwardly presenting surfaces 57 that rest upon the surfaces 35 of the tiles 3 whereby the tiles 5 are suspended from the hanger bars 9. The offsets 33 and flanges 55 obstruct gas passage between the faces of the tiles that are parallel to the bars 9. Gas flow through the mutually contacting faces of the tiles 5 that are transverse to the bars 9 is obstructed by keys 59 and keyways that are similar to keys 35 and keyways 37.

It is apparent that by lifting a tile 5 from its seat on the shoulders 35 that the adjacent tiles 3 may be readily replaced. The use of intermediate tiles 5, of course, increases the spacing of hanger bars 9 and reduces the number of hangers 7 thus lessening the cost of the installation.

The hanger bar 9 may be of other forms than that illustrated in Figs. 1-4 which may be readily made from standard structural elements. For example, in Fig. 5, a hanger bar 65 is illustrated that is constructed from standard cylindrical tubing that has a slot 67 cut in the bottom to receive the shanks of hangers 1. Suitable flanges 69 are welded to the top of the tubing so that the bar may be suspended on beams 4 by bolts 11.

In Figs. 6 and 7, the hanger bar 71 is constructed of two angle bars 73 and 75 that are arranged so that the angles open toward each other. The top edges of the bars 73 and 75 are interconnected to form a structural unit by flanges 77 which are welded thereto and, if desired, the flanges 77 may be extended downwardly and welded to the bottom edges to in-

crease the strength of the assembly. The flanges 77 serve to separate the lower edges of the bars and to provide a slot 79 for the hanger shanks. They also have slots 81 therein to receive bolts 11 whereby the bar 71 may be shiftably suspended from beam 1. It will be observed that the bar 71 is provided at its end with an angle shaped foot 83 that is welded thereto and rests on a ledge 85 of the furnace wall 87. The foot 83 thus serves as an alternate or an additional means of supporting the bar and being obviously applicable to the other forms of hanger bar illustrated herein. It will be observed that in all forms the hanger bars are above the insulation 17 and thus in contact with cool air so that their temperature is low and strength high thus making it possible to eliminate the beams 1, in some cases, without inviting failure of the roof, by supporting the bars on ledge 85.

These and other benefits flow from various structural features of the present structure and it is evident that useful improvements can still be obtained by modifying the construction in certain respects or by employing less than all of the features disclosed herein. These changes will be apparent to those in the art and are within the spirit and scope of the invention.

What is claimed is:

1. In a roof construction, the combination of a plurality of parallel support bars, pairs of tile beneath the bars and extending parallel thereto to form pairs of rows of tile beneath each bar, a common hanger for each pair of tiles, said bars having openings in the bottoms thereof and upwardly presenting surfaces on opposite transverse sides of the openings that are inclined upwardly and outwardly from said openings, said hangers extending upwardly through said openings and having shouldered heads formed on inclines similar to that of said surfaces, said shouldered heads resting on said surfaces and being in one horizontal direction of greater transverse width than the opening in the bars but of less transverse width than the interiors of the bars, and being in another horizontal direction of narrower transverse width than the openings in the bars so that the hangers may be turned and passed through the openings to disconnect them from the bars, said hangers having shank portions extending downwardly from the shouldered heads through the openings in the bars and being of less thickness than the openings in all transverse dimensions, the tiles in said pairs being of substantially identical shape but having the sides transverse to said bar facing in opposite directions, one of the tile sides transverse to the bar having a keyway formed therein and the opposite side having a key formed thereon adapted to fit in said keyway so that the key on one tile is fitted in the keyway of an adjacent tile, the outer top corners of said tiles, with respect to said bars, being cut out to provide offsets having upwardly presenting shoulders, and tiles intermediate adjacent bars having downwardly presenting shoulders resting on said upwardly presenting shoulders so that the tiles are wholly supported thereon, said intermediate tiles having complementary keys and keyways formed therein on opposite sides transverse to said bars so that the keys and keyways on adjacent intermediate tiles are interlocked, the tiles in said pairs contacting each other along the lower portion of a vertical face on each tile, the upper portions of said vertical faces being spaced inwardly from the lower portions, each of the tiles 75

in said pairs having undercut faces upwardly and outwardly inclined from said upper portions of the vertical faces, said shank portions of the hangers extending downwardly between said upper portions and being spaced substantially therefrom, and flanges on the lower end of said shank portions extending outwardly and inclined upwardly from the sides of the hanger in the same vertical plane as the maximum dimension of the hanger head, said flanges engaging said undercut faces so that the reaction forces thereof urge the tiles in each pair toward their contacting vertical faces.

2. In a roof construction, a plurality of parallel hollow hanger bars having openings in the bottoms thereof extending longitudinally of the bars and upwardly presenting internal surfaces on opposite transverse sides of the openings extending upwardly and outwardly on an incline away from the openings, a plurality of hangers suspended from said bars and having heads resting inside said bars on said surfaces, said heads being provided with surface engaging shoulders formed on an incline corresponding to the incline of said surfaces, there being linear engagement of substantial length between said shoulders and surfaces in a direction parallel to the length of the bars, said shoulders being in one horizontal direction of greater transverse width than the opening in the bars but of less transverse width than the interiors of the bars, and being in another horizontal direction of narrower transverse width than the openings in the bars, said hangers being provided with shank portions extending downwardly from the heads through the openings in the bars and which are of less thickness than said openings in all transverse dimensions, said shank portions having transverse feet on the bottom thereof extending outwardly from the sides of the hanger in the same vertical plane as the maximum dimension of the head shoulders, a pair of tiles supported on each of the hangers, there being one tile on each of said feet, the tiles in a pair contacting each other along the lower portion of a vertical face on each tile, the upper portions of the vertical faces being spaced inwardly from the lower portions and having said shank portions extending therebetween and spaced therefrom, each of said tiles having undercut faces upwardly and inwardly inclined from said upper portions of the vertical faces, the inner ends of said feet being spaced inwardly of the outer ends of said undercut faces, and the outwardly extending portions of said feet being inclined upwardly from said shank portions and engaging said undercut faces whereby the tiles on each hanger are urged into contact with each other along the lower portions of said vertical faces by reason of the operation of gravitation.

ROBERT A. BANCK.
